United States Patent Office

Des. 203,301
Patented Dec. 21, 1965

203,301

STRINGED MUSICAL INSTRUMENT

Robert E. Frazier, 122 Walnut Lane,
Santa Barbara, Calif.

Filed Dec. 16, 1964, Ser. No. 83,052

Term of patent 14 years

(Cl. D56—1)

FIG. 1

FIG. 2

FIG. 3

I claim:

The ornamental design for a stringed musical instrument, as shown.
